(57) **CLAIM**

The ornamental design for a dental screw tip elector, as shown and described.

DESCRIPTION

FIG. 1 is a perspective view of a dental screw tip elector, showing my new design;

FIG. 2 is a first side elevation view thereof;

FIG. 3 is a second side elevation view thereof;

FIG. 4 is a third side elevation view thereof;

FIG. 5 is a fourth side elevation view thereof;

FIG. 6 is a first end elevation view of the enlarged tip fragment taken from the circular section 6 indicated in FIG. 3; and, FIG. 7 is a second end elevation of the enlarged tip fragment shown in FIG. 6.

The handle of the illustrated tool is considered environmental structure and is shown in broken lines in the appended drawings. The features shown in broken lines form no part of the claimed invention.
